UNITED STATES PATENT OFFICE.

EMIL CORNELY, OF WASHINGTON, DISTRICT OF COLUMBIA.

EMBROIDERING-MACHINE.

SPECIFICATION forming part of Letters Patent No. 228,445, dated June 8, 1880.

Application filed December 27, 1879. Patented in France March 28, 1879, and in England July 16, 1879.

To all whom it may concern:

Be it known that I, EMIL CORNELY, of Washington city, in the District of Columbia, a resident of the city of Paris, in the Republic 5 of France, have invented certain new and useful Improvements in Embroidering-Machines; and I do hereby declare that the following is a full, clear, and exact description of the construction and operation of the same, reference 10 being had to the annexed drawings, in which—

Figure 1 represents an elevation of said machine, the arm and head to which my present invention is applied being shown in full lines, while all below the cloth-plate is shown in dotted lines, for reference only, as not having any 15 relation to the subject-matter of this invention. Fig. 2 represents an end view of said machine. Fig. 3 represents a detached view of that part of the machine to which my improvements are 20 applied. Figs. 4, 5, and 6 are detached views, hereinafter to be referred to.

My invention relates to the embroidering-machine for which Letters Patent were granted to me as assignee of Antoine Bonnaz on the 25 10th day of November, 1868, No. 83,910, and has for its object the production of an embroidery-stitch which is obtained by winding a second thread at each stitch around the needle or the needle-thread of said embroidering-machine.

The construction and operation of said embroidering-machine being fully known, the drawings and descriptions are limited to the subject-matter of the present invention.

The letters of reference in the drawings for the like parts are the same as those in the specification of the patent of November 10, 35 1868, No. 83,910.

d represents the nipple of the machine, with 40 in which the needle-hook plays to produce the ordinary chain-stitch embroidering-seam.

The nipple *d* is secured to the nipple-tube *H*, which plays within the hub *A* of the casting of the machine, and which is elongated, so 45 as to make room for the gearings, the thread-carrier, the spool and tension of the second thread.

A toothed wheel, *B*, is fitted upon the hub *A*, and can turn thereon freely. It is held in 50 position by means of a ring, *a*, which is screwed to the hub *A*.

The thread-carrier, tension and spool of the second thread are secured to the hub of the wheel *B*, and as the latter turns they revolve all together in a continuous rotating motion 55 around the needle, and wind their thread at each stitch around the needle or the needle-thread.

The thread-carrier *b* is secured to the bar *C* by means of the strap *f*, and the bar *C* is 60 screwed to the hub of the wheel *B*. Within the hub of the bar *C* is also fitted the cylindrical tension-rod *g*, which can be turned by means of its head *h*, as will be explained hereinafter.

The spool *G* of the second thread is secured to the arm *E*, as represented in a horizontal view in Fig. 4. Owing to the very rapid revolution of the entire mechanism around the needle, it is preferred to employ a fixed spool 70 which cannot turn, and which, together with its tension, will take up a small space only, so as to be able to turn within the curved feed-bar *O²*, Fig. 2. A conical spool, *G*, is secured to the arm *E* by means of a bolt, *m*, and screw-nut *k*. The thread is drawn from said fixed 75 spool in the direction of the conical line, and passes through the mouth 1 of the tension-rod *g*, which is in the line of the axis of spool *G*. The thread then passes through the hole 2, 80 and thence into the eye of the revolving thread-carrier *b*. Upon turning the tension-rod *g* by means of the head *h* the thread is wound more or less around the cylindrical surface of rod *g*, and thus its tension can be regulated at pleasure. 85

In employing silk or other twisted thread it happens frequently that the thread does not pass regularly from the spool *G* through the tension *g*. To obviate this difficulty I have 90 applied to the spool *G* a friction-guide, *n*, (represented in detached views in Figs. 5 and 6,) which is secured between the spool *G* and the arm *E* by the pressure of the screw-bolt *m* on its forked end 4, while its front end has a circular opening which fits concentrically against the head 3 of the screw-bolt *m*, leaving a small 95 annular space between the two for the passage of the thread, which then passes through the eye of the thread-guide, and thence into the mouth 1 of the tension-rod *g*. Thus, while the spool, tension, and thread-carrier *b* turn or ro-

tate around the needle, their relative positions to one another do not change, and the second thread is wound regularly at each stitch around the needle or the needle-thread.

5 As I have already stated, the invention relates particularly to the Bonnaz machine, and in order to communicate the requisite motion from the main shaft D of that machine to the thread-carrier b difficulty was experienced on account of the shaft W, by which the feed motion is directed, the position of which cannot be changed without modifying considerably, if not entirely, the construction of the machine. The employment of outside shafting and gearing for this purpose renders the machine too complicated for efficient use. The difficulty is overcome by means of a sleeve or hollow shaft, M, Figs. 1 and 3, which is fitted into the casting of the machine, or is only slipped over the shaft W in such a manner that both shafts M and W can turn or rotate independently one of the other.

The cogged wheel N is secured to one end of the sleeve M and receives its rotary motion from the pinion Q, which is secured to the main shaft B. The pinion R, which is secured to the other end of the sleeve M, imparts a rotary motion to the pinion T and to the cogged wheel K, which both are secured to the vertical shaft p, and which transmit their motion to the wheel B and to the thread-carrier b by means of the intermediate pinion, L, while the free rotation of the shaft W is in no way obstructed by the rotation of sleeve M.

35 It is evident that the sleeve M and the gearings N and R may be made of one and the same piece, and must be considered as such in their operation.

By ungearing the wheels Q and N the motion of the thread-carrier b is arrested, and the machine makes the ordinary chain embroidery-stitch. This can be done by loosening the screws which secure the wheel Q to its shaft D, and by shifting it thereon so as not to be in gear with pinion N, or by the employment of any suitable coupling device. Such devices being well known to those skilled in the art, no description is deemed necessary.

I have shown on the drawings a conical fixed spool; but a common thread-spool, set 50 upon and supported by a vertical pin, can be employed without securing it in any way, and, notwithstanding the high speed of revolution, it will cause no irregularity in the tension.

Having thus fully described the nature of 55 my invention, what I claim therein as new, and desire to secure by Letters Patent, is--

1. The combination, with the thread-carrier for delivering a second thread to be wound around the ordinary needle-thread of a sewing 60 or embroidering machine and the needle-bar of said machine, of a rod or pin for supporting at the side of the needle-bar the spool from which the aforesaid second thread is drawn, and mechanism for revolving together around the axis 65 of the needle-bar said thread-carrier and spool pin or rod, substantially as described.

2. The combination of the rod or pin for supporting the spool from which the second thread is drawn, a tension device, and a thread-carrier, 70 all connected with the same pinion, and means for supporting said parts and for revolving them around the axis or path of the needle of a sewing or embroidering machine, substantially as described.

3. The combination, in a sewing or embroidering machine having a top feed, with the main shaft rotating in the goose-neck and a shaft located below the main shaft for directing the feed motion, of a sleeve or hollow shaft 80 encircling the feed-shaft and provided with gears on opposite ends, and a thread-carrier and connections and gears for communicating motion from the main shaft, through the said sleeve or hollow shaft and its gears, to the 85 thread-carrier, substantially as described.

4. The combination, with the pin or rod for supporting a spool in a fixed position, of the bent plate, having a circular opening at one end and at the other a slot which fits over 90 said pin or rod, and a device for securing said plate in position, substantially as described.

E. CORNELY.
